UNITED STATES PATENT OFFICE.

JOSEPH J. RING, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

ROTARY MACHINE.

Application filed June 29, 1925. Serial No. 40,136.

This invention relates in general to improvements in rotary machines, and relates more specifically to improvements in the construction and operation of the rotors of rotary machines which are adapted to either propel or to be propelled by fluid, the invention being especially capable of adaptation in fluid pumps or turbines.

An object of the invention is to provide an improved rotary machine which is simple in construction and efficient in operation. Another object of the invention is to provide improved mechanism for controlling the operation of rotary machines. A further object of the invention is to provide an improved rotor structure especially applicable to rotary machines which are operable at relatively high speeds. Still another object of the invention is to provide simple and efficient means for effecting angular adjustment of the vanes of a rotor either while the rotor is in motion or while it is at rest. A further object of the invention is to provide means for effectively locking the movable vanes of rotor or the like in adjusted position. Additional objects and advantages of the invention will be apparent in the course of the following description.

Some of the novel features of rotor vane adjustment shown but not specifically claimed herein, form the subject-matter of a co-pending application Serial No. 35,517, filed June 8, 1925.

A clear conception of an embodiment of the present invention and of the operation of devices constructed in accordance therewith, may be had by referring to the drawing accompanying and forming a part of this specification in which like reference characters designate the same or similar parts in the various views.

Fig. 1 is a central vertical section through a vertical hydraulic turbine installation comprising an axial flow rotor having adjustable vanes.

Fig. 2 is a fragmentary enlarged central vertical section through a portion of the improved turbine rotor and through the main shaft thereof.

Fig. 3 is a top view of the vane adjusting and position indicating mechanism.

Fig. 4 is an enlarged fragmentary central vertical section through another form of

vane adjusting and position indicating mechanism.

Fig. 5 is a part sectional top view of the improved vane adjusting and position indicating mechanism shown in Fig. 4.

While the invention has been specifically shown and will be described herein as being applied to an axial flow hydraulic turbine rotor, it will be apparent that at least some of the features of the present improvement are more generally applicable to rotors of various kinds, such as pumps, blowers, propellers, steam turbines, etc. The hydraulic turbine unit illustrated in the drawing, comprises in general a rotor 2 having a plurality of vanes 3 radiating from a central hub 4 which is secured to the lower flange of a hollow main shaft 5; a main turbine casing 6 forming an inlet chamber 8 for conducting water from a penstock or flume 14 toward the rotor 2 in the form of a vortex and in an axial direction; and a draft tube 11 for conducting water from the rotor 2 to the tail race 12 in a well known manner.

The dovetail shaped radiating vanes 3 of the rotor 2 are pivotally associated with the hub 4, the inner extremity of each vane 3 being provided with a plurality of concentric cylindrical bearing portions 18, 19, 20 which are journaled within the hub 4, and the axes of all of which lie in a common plane disposed perpendicular to the axes of the rotor 2. The hub 4 is split, being formed of upper and lower sections detachably connected to each other and to the lower flange of the main shaft 5, the hub being split in the plane of the axes of the vane pivots and the upper hub section having an integral central projection 21 extending into the lower section, and having the vane portions 20 journaled therein. Each of the vanes 3 has a bevel gear segment 17 formed integral therewith between the bearings 19, 20 thereof, the lower hub section 47 being formed as a continuous ring and coacting with the outer side surfaces of all of the segments 17 as shown in Fig. 2 in order to retain the vanes against displacement away from the hub 4. Located

within the hollow main shaft 5 of the turbine, is an auxiliary or adjusting shaft 15 which besides passing entirely through the main shaft 5 as illustrated in Fig. 2 also ex-

tends downwardly through the central projection 21 of the upper section of the hub 4. The lower extremity of the adjusting shaft 15 is provided with a bevel pinion 16 which 5 coacts with the gear segments 17 of the vanes 3. A removable cap 10 secured to the lower hub section encloses and protects the gearings 16, 17.

The mechanism for effecting adjustment 10 of the vanes 3 about their pivotal axes, is associated with the upper extremity of the adjusting shaft 15 as shown in Figs. 1, 2 and 3. A mutilated worm wheel 22 is splined upon the upper extremity of the shaft 15 by 15 means of a spline 30 and has a lower surface which coacts with an upper surface of a support 29 secured to the upper extremity of the hollow main shaft 5. A worm shaft 23 is carried in bearings formed integral 20 with the support 29, the shaft 23 having an adjusting nut 32 associated with one end thereof, a locking nut 31 associated with the opposite end thereof, and a worm 24 formed on its medial portion. The worm 24 coacts 25 with the teeth 25 of the worm wheel 22, and the worm wheel 22 has an indicator 26 formed integral therewith and cooperating with a dial 27 carried by the support 29. A locking set screw 28 cooperates with the 30 vane adjusting shaft 15 and with the upper extremity of the segment 22 the cooperation being such that the entire shaft 15 together with the pinion 16 may be moved longitudinally within the hollow main shaft 35 5 by manipulation of the set screw 28.

In the modified form of rotor vane adjusting mechanism shown in Figs. 4 and 5 the adjusting means is disposed between flanges 34, 36 formed respectively on the upper and 40 lower sections of the hollow main shaft 5. In this embodiment of the invention the upper shaft section 33 need not be bored as in the embodiment of Fig. 2. The flanges 34, 36 are separated to permit insertion of an 45 intermediate member 35 which is recessed to receive the various adjusting elements. The mutilated worm wheel 38 is rotatable with the upper extremity of the adjusting shaft 15 by virtue of a spline as previously described, and cooperates with a worm wheel 37 formed integral with the medial portion of a worm shaft 46 mounted within the member 35 and capable of rotation by virtue 50 of a polygonal end projection. The worm wheel 38 carries an indicator 41 cooperating with a dial 42 associated with the lower flange 36. The upper extremity of the adjusting shaft 15 is further provided with a recess 43 which receives prongs formed integral with a locking worm wheel 39. The worm wheel 39 is mounted for movement 60 along the screw threads of a stud 40 which is rigidly attached to the member 35. The teeth of the worm wheel 39 coact with a worm carried by a locking shaft 44 which is

supported in the member 35 and is prevented from moving endwise by means of a groove and pin 45. The shaft 44 is capable of rotation by virtue of a polygonal end projection thereon and rotation of the shaft 44 causes the worm wheel 39 to move longitudinally upon the screw threads of the stationary stud 40.

The hollow main shaft 5 which supports the rotor 2 and the mechanism for adjusting the vanes thereof, is mounted in suitable bearings in the main casing 6 and in the frame of a generator 9 or other energy translating device. The casing 6 and the generator 80 9 are supported upon suitable foundation structure 13, and the casing 6 may be provided with an annular series of adjustable guide vanes for controlling the flow and 85 properly conducting the water from the flume 14 to the transition space 8. During 90 normal operation of the unit, the vanes 3 are locked to the hub 4 in an adjusted position, and water is admitted from the flume 14 past the guide vanes 7 and through the transition space 8 to the rotor 2 from which the 95 water is discharged through the draft tube 11 to the tail race 12. The quantity of water thus admitted to the rotor may be varied in a well known manner, by adjustment of the 100 guide vanes 7. The vortex of liquid produced by the guide vanes 7 and entering the rotor 2 from the vane-free transition space 8, produces rotation of the shafts 5, 15 and of the rotor of the energy translating 105 device 9.

Referring specifically to the embodiment of the invention shown in Figs. 1, 2 and 3, if it is desired to effect angular adjustment of the rotor vanes 3 about their pivotal axes, it is necessary to shut off the flow of operating fluid and to stop the unit. When the rotor is at rest, the vanes 3 may be unlocked by releasing the set screw 28 thereby permitting the internal shaft 15 and the pinion 16 to drop slightly and freeing the gear segments 17. Upon release of the set screw 28, the lock nut 31 may also be released whereupon the worm 24 is free to be rotated by the application of a wrench to the shaft end 32. Rotation of the worm 24 produces rotary movement of the gear segment 22, of the operating shaft 15, of the pinion 16 and of the segments 17, thus causing the vanes 3 to simultaneously rotate about their pivotal axes. It will be apparent that by rotating the worm 24 in one direction the vanes 3 will be tilted in a predetermined direction, and that opposite rotation of the worm 24 will result in opposite tilting of the vanes 3. The indicator 26 cooperating with the dial 27 clearly indicates the position of adjustment of the vanes 3. When the vanes 3 have been properly adjusted, they may be locked in adjusted position by manipulation of the set screw 28 to raise the shaft 15 and to 110 115 120 125 130

wedge the pinion 16 against the segments 17 of the vanes.

Referring specifically to the embodiment of the invention shown in Figs. 4 and 5, if it is desired to effect angular adjustment of the rotor vanes about their pivotal axes, the unit must be shut down as previously explained whereupon the vanes may be unlocked by rotating the shaft 44 with the aid of a socket wrench applied to the polygonal shaft end. The rotary movement of the shaft 44 is transmitted to the locking worm wheel 39 coaxing with the fixed stud 40, and causes the worm wheel 39 to move downwardly upon the stud 40 thereby permitting the shaft 15 to drop sufficiently to release the bevel gearing 16, 17. After the elements have been unlocked, the internal shaft 15 may be rotated to effect the desired vane adjustment, by turning the worm 37 coaxing with the worm wheel 38. During adjustment of the vanes 3, the indicator 41 cooperating with the dial 42 clearly indicates the degree of adjustment and the position of the vanes. When proper adjustment of the vanes has been effected, the locking shaft 44 and gear 39 may again be manipulated to cause the gear 39 to ride upwardly along the stud 40 and to firmly lock the shaft 15 and bevel gears 16, 17 in adjusted position.

It will be apparent that the vane adjusting mechanisms are readily accessible from the exterior of the turbine casing 6 and that the locking device effectively maintains the vanes 3 in adjusted position. The rotor 2 may be readily dismantled by removing the cap 10 and the clamping bolts which normally hold the hub sections together, whereupon the vanes 3 are released and removable. The lower hub section 47 coacts with the outer surfaces of the segments 17 and thereby prevents outward displacement of the vanes 3, and the plural bearings 18, 19, 20 for each vane 3 effectively retain the vanes in position. It will be understood that only slight adjustment of the vanes 3 is ordinarily desired thereby permitting the use of relatively narrow gear segments 17 and reducing the diameter of the hub 4 to a minimum.

It should be understood that it is not desired to limit the invention to the exact details of construction and operation herein shown and described for various modifications within the scope of the claims may occur to persons skilled in the art.

It is claimed and desired to secure by Letters Patent:

1. In combination, a main shaft, a vane pivotally associated with said main shaft, an adjusting shaft disposed concentrically of said main shaft, motion transmitting mechanism connecting said adjusting shaft with said vane, means for relatively rotating said main and said adjusting shafts to vary the

angularity of said vane about its pivotal axis, and means for axially shifting said adjusting shaft to positively lock said vane in an adjusted position.

2. In combination, a main shaft, a hub secured to said shaft, a vane pivotally supported by said hub, gearing associated with said vane adjacent to its pivot, an adjusting shaft, motion transmitting mechanism connecting said adjusting shaft and said gearing, and means for axially shifting said adjusting shaft to lock said gearing in an adjusted position.

3. In combination, a main shaft, a hub secured to said shaft, a plurality of vanes radiating from the axis of said main shaft and pivotally supported by said hub, a gear associated with each of said vanes adjacent to its pivot, an adjusting shaft disposed concentrically of said main shaft, a gear carried by said adjusting shaft and meshing with said vane gears, and means for moving said adjusting shaft gear along the axis of said main shaft to lock said vane gears in adjusted position.

4. In combination, a hollow main shaft, a hub secured to said shaft, a plurality of vanes pivotally supported by said hub, a gear associated with each of said vanes adjacent to its pivot, an adjusting shaft located within said main shaft and extending through said hub, a gear connecting said adjusting shaft and said vane gears at the side of said hub remote from said hollow shaft, and means for axially moving said adjusting shaft gear to lock said vane gears in adjusted position.

5. In combination, a hollow main shaft, a hub secured to said shaft, a plurality of vanes pivotally supported by said hub, a bevel gear associated with each of said vanes adjacent to its pivot, an adjusting shaft located within said hollow shaft, a bevel pinion secured to said adjusting shaft and coacting with said bevel gears, and means for shifting said pinion axially to lock said gears in adjusted position.

6. In combination, a hollow main shaft, a hub secured to said shaft, a plurality of vanes pivotally supported by said hub, a bevel gear segment rigidly attached to each of said vanes adjacent to its pivot, an adjusting shaft located within said main shaft and extending through and beyond the pivotal axes of said vanes, a bevel pinion secured to the end of said adjusting shaft at the side of said hub remote from said main shaft and coaxing with all of said gears, and means for axially shifting said pinion to lock said vanes in adjusted position.

7. In combination, a hollow main shaft, a hub secured to said shaft, a plurality of vanes pivotally supported by said hub, a bevel gear associated with each of said vanes adjacent to its pivot, an adjusting shaft lo-

- cated within said main shaft and extending through said hub, a bevel pinion connecting said adjusting shaft and said gears at the side of said hub remote from said hollow shaft, means associated with a medial portion of said main shaft for adjusting said vanes through said pinion and gears, and means for axially shifting said pinion to lock said vanes in adjusted position.
- 10 8. In combination, a hollow main shaft, an energy translating device cooperating with one end of said main shaft, a hub secured to the opposite end of said main shaft, a plurality of vanes pivotally supported by said hub, a bevel gear associated with each of said vanes adjacent to its pivot, an adjusting shaft located within said main shaft, a bevel pinion connecting said adjusting shaft and said gear, means associated with said main shaft between said device and said hub for relatively rotating said shafts to adjust the angularity of said vanes through said pinion and said gears, and means for axially shifting said pinion to wedge the same between said gears.
9. In combination, a main shaft, a vane pivotally associated with said shaft, an adjusting shaft disposed concentrically of said main shaft, means for relatively rotating said shafts to vary the angularity of said vane about its pivotal axis, and means for relatively moving said shafts longitudinally of each other to positively lock said vane in an adjusted position.
10. In combination, a main shaft, a plurality of vanes pivotally associated with said shaft, an adjusting shaft associated with said main shaft, means for relatively rotating said shafts to simultaneously adjust said vanes about their pivotal axes, and means for relatively moving said shafts longitudinally of each other to lock said vanes in adjusted position.
11. In combination, a hollow main shaft, a vane pivotally associated with said shaft, an adjusting shaft disposed within said main shaft, means for relatively rotating said shafts to adjust said vane about its pivotal axis, and means for relatively moving said shafts longitudinally of each other to lock said vane in an adjusted position.
12. In combination, a hollow main shaft, a plurality of vanes pivotally associated with said shaft, an adjusting shaft within said main shaft, means for relatively moving said shafts to simultaneously adjust said vanes about their pivotal axes, and means for relatively moving said shafts to positively lock said vanes in adjusted position.

In testimony whereof, the signature of the inventor is affixed hereto.

JOSEPH J. RING.
